UNITED STATES PATENT OFFICE.

PHILIP A. MEANS, OF CAMBRIDGE, MASSACHUSETTS.

FOOT-THROTTLE-CONTROLLING MECHANISM FOR AUTOMOBILES.

Application filed February 8, 1923. Serial No. 617,783.

To all whom it may concern:

Be it known that I, PHILIP A. MEANS, a citizen of the United States, residing at Cambridge, in the county of Middlesex and State of Massachusetts, have invented certain new and useful Improvements in Foot-Throttle-Controlling Mechanism for Automobiles; and I do hereby declare the following to be a full, clear, and exact description 10 of the invention, such as will enable others skilled in the art to which it appertains to make and use the same.

The present invention relates to an improvement in foot throttle controlling mechanism for automobiles.

The object of the invention is to reorganize and improve foot throttle controlling mechanism, and to this end the invention consists in the mechanism hereinafter described and particularly defined in the claims.

In the accompanying drawing Fig. 1 is a plan of the mechanism; Fig. 2 is a side elevation; and Fig. 3 is an end elevation looking from the right hand end of Fig. 2.

In the accompanying drawing illustrating the invention the throttle push rod 10 rises through the foot board at right angles to the same, so that a movement thereof toward 30 the floor board opens the throttle, it being connected below the floor board therewith. The head 11 of the throttle push rod is an inclined plate. By moving the foot laterally across this inclined surface the throttle push rod is depressed and the throttle opened. Mounted on the floor board alongside the throttle push rod is a block 12 provided 35 with a groove 13 at its center, and having two foot rest portions 14 in front of and behind the groove 13. These foot rest portions 14 are covered with steel wear plates 40. In the groove 13 is mounted the foot pusher 16, which is provided with a slide piece 17 which, in turn, is received in the 45 guide 18 so that the foot pusher may slide back and forth in the guide 18 toward and from the foot throttle 10. A spring 19 fastened at the left hand end to a cross bar 20 and at its right hand end to the foot 50 pusher 16, normally tends to move the foot pusher to the left. The foot pusher in the 55 position shown in the drawings is at the extreme limit of its right hand movement with the spring 19 under tension. When the foot is removed from the foot rest the spring pulls the foot pusher toward the left until

the end of the slide 17 strikes the stop 21, which is shown as a pin inserted in the block adapted to engage the end of the slide 17 and limit its movement. A similar pin 22 at the 60 other end of the slot limits the movement of the foot pusher to the right. The normal operative position, therefore, of the foot pusher is that shown in dotted lines at 23.

In operation the operator places his foot 65 on the left hand end of the foot rest, presses the right hand side of his foot against the foot pusher 16, and moves it to the right, thereby putting the spring 19 under tension. At idling speeds a gentle pressure of the 70 foot on the foot rest will be sufficient to hold the foot pusher in the position shown in Fig. 2. Now, when the operator desires to open the throttle, he reduces the pressure of his foot on the foot rest, and the foot pusher 75 is thereby allowed to push the foot to the left, causing it to be pushed out on the inclined head 11 of the throttle push rod. This depresses the throttle push rod and opens the throttle. By the application of a 80 gentle pressure to the foot, a pressure which ordinarily will not necessarily exceed the weight of the foot on the foot rest, the foot is held from movement, and the throttle is held open to the desired degree without any 85 fluctuation or jumping due to the throwing of the car in passing over irregularities of the road surface. By moving the foot to the right and stretching the spring, the 90 throttle will be allowed to rise, the usual springs being employed which normally tend to maintain the throttle in the position shown in Fig. 2.

So far as I am aware it is broadly new in throttle controlling mechanism to provide 95 means for moving the foot in a direction to open the throttle.

The illustrated embodiment of the present invention is a cheap and simple construction, the block 12 being made of wood, and the 100 other parts being of simple material and construction. If desired the mechanism may be entirely constructed in metal, and the invention is not to be considered to be limited to the illustrated embodiment, as it may be 105 made in a wide variety of forms without departure therefrom.

Having thus described the invention, what is claimed is:

1. Throttle controlling mechanism for 110 automobiles having, in combination, a throttle actuating member provided with an

inclined head, a foot rest on one side of the throttle controlling member having a foot supporting surface located at the level of the lower end of the head of the throttle push rod, a foot pusher movably mounted on the foot rest, and means for actuating it to push the foot of the operator resting on the foot rest in the direction to engage and press down the throttle push rod.

10 2. Throttle controlling mechanism for automobiles comprising a throttle push rod provided with an inclined head, a foot pusher, and means for moving it located adjacent to the inclined head of the push rod and adapted when pressure on the foot is released to push the foot on the inclined head and thereby to depress the throttle push rod and open the throttle.

15 3. Throttle controlling mechanism for automobiles having, in combination, a throttle controlling member provided with an inclined head, a foot pusher adapted to

engage one side of the foot, and means for actuating the foot pusher to push the foot on the inclined head of the throttle controlling member so as thereby to move it.

20 4. Throttle controlling mechanism for automobiles having, in combination, a throttle controlling member provided with a groove located adjacent to the lower end of the inclined head of the throttle controlling member, a foot pusher slidably mounted in the groove in the block, and a spring connected with the foot pusher and normally tending to move it toward the head of the throttle controlling member.

25 5. Throttle controlling mechanism for automobiles having, in combination, a throttle operating member, a foot pusher adjacent thereto, and means for actuating the pusher to push the foot in the direction to actuate the throttle operating member.

30 35 40 PHILIP A. MEANS.
